UNITED STATES PATENT OFFICE.

WILLIAM W. WEITLING, OF COLLEGE POINT, NEW YORK.

DESIGN FOR A BATTERY JAR.

Application filed March 8, 1922. Serial No. 1,077. Term of patent 14 years.

To all whom it may concern:

Be it known that I, WILLIAM W. WEITLING, a citizen of the United States, residing at College Point, in the county of Queens and State of New York, have invented a new, original, and ornamental Design for Battery Jar, of which the following is a specification, reference being had to the accompanying drawing, forming part thereof.

Figure 1 is a side view, and Figure 2 is an end view of a battery jar, showing my new design.

I claim:

The ornamental design for a battery jar, as shown.

In testimony whereof I have signed this specification in the presence of two subscribing witnesses.

WILLIAM W. WEITLING.

Witnesses:

F. S. MORGAN,
WM. WENZ.

Certificate of Correction.

It is hereby certified that Design Letters Patent No. 62,295, granted May 1, 1923, upon the application of William W. Weitling, of College Point, New York, for a design for "A Battery Jar," were erroneously issued to the inventor, said Weitling, whereas said Letters Patent should have been issued to *American Hard Rubber Co., of New York, N. Y., a Corporation of New York*, said corporation being assignee of the entire interest in said invention, as shown by the records of assignments in this office; and that the said Letters Patent should be read with this correction therein that the same may conform to the record of the case in the Patent Office.

Signed and sealed this 19th day of June, A. D., 1923.
